UNITED STATES PATENT OFFICE.

SAMUEL K. WHITE, OF CHICAGO, ILLINOIS.

PAGING-MACHINE.

SPECIFICATION forming part of Letters Patent No. 449,304, dated March 31, 1891.

Application filed October 23, 1888. Serial No. 288,950. (No model.)

To all whom it may concern:

Be it known that I, SAMUEL K. WHITE, of Chicago, in the county of Cook and State of Illinois, have invented certain new and useful 5 Improvements in Paging-Machines; and I do hereby declare that the following is a full, clear, and exact description thereof, reference being had to the accompanying drawings, and to the letters of reference marked thereon, 10 which form a part of this specification.

This invention relates to paging or numbering machines of that class embracing a series of printing-wheels or type-disks mounted upon a common shaft, which disks are in the 15 operation of the machine automatically turned to present the proper numbers for printing.

The invention embraces improvements in the devices for supporting and for giving bodily movement to the disks; in a novel repeating mechanism, or means by which the same 20 number may be printed successively two or more times, if desired; in means for inking the type-disks, and in other details of construction in such machines; and it consists in the 25 matters hereinafter described, and pointed out in the appended claims.

In the accompanying drawings, illustrating my invention, Figure 1 is a central vertical section of a machine embodying the same. 30 Fig. 2 is a front elevation of the lower part of the machine, or that portion below the type-disks. Fig. 3 is an enlarged detail side elevation of the parts adjacent to the type-disks as viewed from the side of the machine opposite 35 site to that seen in Fig. 1. Fig. 4 is a front elevation of the parts shown in Fig. 3. Fig. 5 is a detail elevation showing the inking devices only and illustrating the same in changed positions by dotted lines. Fig. 6 is a detail 40 side view of the parts concerned in turning the type-disks, illustrating the same in changed positions in dotted lines. Fig. 7 is a detail section illustrating the repeating mechanism, taken upon line 77 of Fig. 6. Fig. 8 is a detail 45 plan view of said repeating mechanism. Fig. 9 is a detail section taken upon line 99 of Fig. 3. Fig. 10 illustrates in side elevation the ink-fountain illustrated in Fig. 9 removed from the machine. Fig. 11 is a detail section 50 taken upon line 1111 of Fig. 1, showing the power-driving devices. Fig. 12 is a detail plan section of the overhanging frame-arm, taken

upon line 1212 of Fig. 1. Fig. 13 is an enlarged detail section through the type-disks, taken upon line 1313 of Fig. 1. Fig. 14 is a 55 cross-section through the type-disks support, taken between two of the disks on line 1414 of Fig. 13. Fig. 15 is a detail view illustrating the notched disks of the repeating mechanism removed from the machine. Fig. 16 is 60 a detail side view showing a modified form of the parts of the repeating mechanism adjacent to the notched disks. Fig. 17 is a plan view of the parts shown in Fig. 16.

As shown in the said drawings, A is the 65 main part of the machine-frame, consisting of a hollow or tubular standard, which rests upon the floor at its base and is provided at its upper end with an overhanging arm or goose-neck A', at the end of which the type 70 wheels or disks and devices by which they are immediately actuated are located.

The machine is adapted for actuation both by a foot-lever and by power, and the devices for transmitting motion from said foot-lever 75 and from a counter-shaft located upon the standard A at the lower part thereof to the printing-disks are located within the said tubular frame-standard, so that said devices are concealed from view, and the machine 80 presents to the eye a simple and compact appearance.

B is the work-table, which is supported by means of a sliding bracket B', sustained upon a vertical bracket B², which is attached at its 85 lower end to the frame-standard A. The said bracket B² is provided at its upper end with a stationary piece or plate B³, which is arranged beneath the type-disks and sustains the sheet to be printed while the impression 90 is being made.

The work-table B is intended for supporting a book or other bulky article, and is movable vertically, while the surface B³, which takes the pressure in printing, is stationary, 95 this arrangement of the parts being old and common in similar machines.

C is a type-disk-carrying arm, which is supported upon a pivot C' on the frame, and is provided at its free end with a curved plate 100 C², which is held and guided between curved guides a a at the end of the arm A' of the frame.

The numbering disks or wheels D D are

mounted upon a stud C³, Figs. 4, 6, and 13, which stud is secured to a single rigid laterally-arranged arm C⁴, Fig. 4, upon the lower end of the sliding plate C². The disks are 5 provided with peripheral types, in the usual manner, and are provided, also, with devices whereby one disk is moved one-tenth of a rotation after each complete revolution of an adjacent disk, and which may be of any well-known or preferred construction. In the particular machine shown these devices are located between the disks, so that they do not appear in the drawings, (except partially in Figs. 13 and 14,) and inasmuch as such devices are common and well known they are 15 not made the subject of special illustration and description herein.

The type-disks are immediately supported by means of a sleeve D', adapted to fit over 20 the stud C³, by which the wheels are supported upon the arm C⁴ of the sliding plate C², the said sleeve being provided with collars c and c' at its ends, forming shoulders by which the several disks are held upon the sleeve, so that 25 the sleeve, with the several disks thereon, may be removed from the machine without disturbing the relative position of the disks. As herein shown and preferably constructed, the collar c' is formed by a ring of greater 30 external diameter than the sleeve, and is secured to the end of the latter by screws, as shown, Fig. 13, while the collar c surrounds the sleeve and is held thereon by a radial setscrew or otherwise. The said sleeve and all 35 the disks thereon may be turned upon the stud for bringing the types which are in position for printing forwardly or upwardly toward the operator, to enable the same to be cleaned or inspected when desired. For convenience in thus turning the sleeve the latter 40 is herein shown as provided with a milled flange c² upon the collar c. The said sleeve D' is conveniently held upon the stud C³ by means of a thumb-screw D², inserted in the 45 end of the stud and provided with a flange or shoulder adapted to bear against the end of the said sleeve, as clearly shown in the drawings, Fig. 13.

A vertical reciprocatory movement is given 50 to the arm C, plate C², and parts connected therewith for the purpose of carrying the type-disks toward and from the table by devices constructed as follows: E is a rocking lever, which is mounted upon the pivot-pin C' and is located within the frame-standard 55 at the side of the carrying-arm C. The said lever E is curved or bent to correspond with the shape of the arm A' of the standard, and the free end of the lever is engaged with the 60 upper part of the plate C². The said plate C² and the guides a therefor are, as before described, conformed to a circular curve concentric with the pivot C' of the arm C. When 65 said lever E is moved or oscillated about its pivot, therefore, it will, by its engagement with the plate C², give an oscillatory movement to said plate and the arm C. Said plate C² is

provided with a longitudinal groove or recess in its rear or inner surface, the end of the rocking lever E being inserted in the upper part of said groove or recess. Within the longitudinal groove or recess of said plate C², between a transverse part of the said plate at the bottom of the groove and the under surface of the said arm, is placed a spirally-coiled spring E'. Said spring E', being thus located, obviously serves to transmit the downward pressure of the arm E to the plate C² when the arm is moved downwardly. Said spring is made of sufficient stiffness to give 80 suitable pressure for printing under ordinary circumstances, but is adapted to yield, and thereby allow the stoppage of the downward movement of the type-disks in case said type-disks strike any obstruction affording such 85 resistance as would tend to break or injure said type-disks or the parts supporting them. Such spring furthermore serves to compensate for differences in the thickness of the pile of sheets or book-leaves beneath the disks, 90 it being entirely obvious that the said spring will allow the type-disks to yield upwardly when necessary to prevent a too forcible pressure upon the printing-surface, such as is liable to occur when a relatively-thick pile of 95 sheets or leaves is upon the table. In other words, said spring is adapted to yield upon the occurrence of any excess of pressure above that necessary for printing, so that the machine is adapted to operate upon piles of paper, sheets, or cards of varying thickness. 100 This is a matter of great convenience for the reason that to facilitate the handling of the sheets to be numbered a pile of the same is commonly placed upon the table of the machine and the sheets then withdrawn one by 105 one as printed.

Devices are herein provided for automatically turning the first or end disk of the series of type-disks, which contains the types indicating units, one step at each reciprocation of the disks, such devices operating by the bodily motion of the disks (or plate carrying the same) with reference to the frame. Such devices are constructed as follows: d' d' 115 are ratchet-teeth upon the outside face of the type-disk, which is at the right-hand side of the several type-disks, and which contains the types by which the numerals expressing units are printed. Rotative motion is given 120 to the first disk only by the actuating devices, the other disks being turned in their order by automatic devices located between the disks and operating to turn each disk one-tenth of a rotation at the completion of 125 each rotation of the adjacent disk to the right of it, as hereinbefore mentioned. F, Fig. 6, is an oscillating arm mounted upon a collar c³ of the stud C³ between the arm C⁴ and the end of the sleeve D', and F' is a spring-pawl 130 pivoted to the said arm F and engaging the ratchet-teeth. To the arm F is rigidly affixed a second arm F². Said arm F² is arranged in an approximately-horizontal position, and its

outer or free end is pivotally connected with a connecting-bar F^3 , the upper end of which is pivoted to the side of the frame-arm A' . When the plate C^2 and type-disks thereon are reciprocated vertically by the action of the lever E , the arm F will obviously be caused to swing about its pivotal axis by reason of the connection of the outer end of the arm F^2 with the frame, so that at each downward movement of the disks the pawl will be carried backwardly over one of the ratchet-teeth d' , and in the upward movement of the said disks the disk D , upon which the ratchet-teeth are formed, will be turned one-tenth of a rotation.

For the purpose of holding the several type-disks from movement during the time the said disks are being moved downward and the impression is being made, the sleeve D' is provided with a series of longitudinal grooves equal in number to the types upon each disk, said grooves being engaged by spring-pawls d^2 , d^2 , Figs. 13 and 14, upon the several disks. The said spring-pawls are arranged to engage the grooves with sufficient force to prevent accidental turning of the disks, and at the same time to easily yield and pass out of the grooves when the disks are turned in the operation of the machine. Similarly-acting spring-pawls have, however, been heretofore used for the same purpose, and this feature of construction forms no part of the present invention.

It is obviously necessary that the sleeve D' should be held from turning upon the stud C^3 as the disks are turned in the usual operation of the machine, and to hold said sleeve immovable upon the shaft, while at the same time enabling it to be released and turned upon said stud at desired times for purposes hereinbefore stated, a locking device is provided upon the arm C^4 or other adjacent stationary part, said locking device being adapted to detachably engage the said sleeve. A simple and convenient form of such locking device is illustrated in the drawings, Fig. 13, the same consisting of a sliding pin C^5 , which is inserted in a guide-aperture in the arm C^4 , passes through the collar c^3 , and engages a hole or recess c^1 in the adjacent end of the sleeve. The said pin is provided at its outer end with a knob or handle c^5 , by which it may be moved, and with a shoulder or collar c^6 near its inner end, which collar is located within an enlargement or recess c^7 , formed in the said arm C^4 and opening at the inner face of the arm. Within the said recess c^7 , between the bottom or outer end thereof and the said collar c^6 , is placed a spiral spring c^8 , which tends to hold the pin engaged with the sleeve. The handle c^5 is provided with an annular flange c^9 , which rests against the outer face of the arm C^4 , and is provided with an eccentric stud or pin c^{10} , adapted to enter a recess c^{11} in the arm C^4 , and thereby allow the end of the pin to engage with the sleeve in one position of the said handle c^5 . When the pin

is pulled out and the handle is turned partially around, however, said stud c^{10} will rest against the surface of the arm C^4 , and thereby prevent the engagement of the pin with the recess of the sleeve, at which time the sleeve may be freely turned for cleaning the type-disks or other purposes, as hereinbefore set forth.

Devices for operating the rocking-lever E , both by the foot of the operator and by steam or other power acting through a rotating shaft, are provided as follows: Upward movement of the free end of said lever E , by which the type-disks are carried upwardly or away from the work-table, is produced by a spring acting upon the said lever. In the particular construction illustrated said lever is provided adjacent to its pivot e with a rigid horizontally-extending arm E^2 , which projects through a slot in the rear part of the frame-standard A , and is connected with the upper end of a coiled spring G , the lower end of which is attached to a rearwardly-extending lug G' , cast upon or otherwise secured to the said frame-standard. Said lever E is provided with a downwardly-extending rigid arm E^3 , located within the hollow frame-standard, which arm E^3 is engaged at its lower end with the upper end of a lever H , mounted upon a pivot h , which passes through the lever at a point between its ends. Said lever is arranged in an approximately vertical position within the frame-standard, and has its upper end engaged with the front surface of the lever-arm E^3 . The lower end of the lever H engages the upper end of an arm I' , attached to a foot-lever I , which is mounted upon a pivot i near the base of the machine, said foot-lever I extending outwardly through a slot in the frame-standard to a position convenient for the foot of the operator standing at the table B .

Devices are provided for actuating the machine by power, such devices being adapted to operate independently of the foot-lever I , and being shown in Figs. 1 and 11. As illustrated in said figures, H' is a short shaft, which is mounted horizontally in a bracket A^3 upon the frame-standard at the rear of the same and adjacent to the pivot h of the lever H . Said shaft H' is provided with a cone-pulley H^2 , and also with a crank-disk H^3 provided with a crank-pin h' , which is arranged in the same vertical plane with or opposite the lever H .

H^4 is a horizontally-arranged arm, which is pivoted upon the pivot-pin h , and is provided with a horizontal slot h^2 , which is engaged by the crank-pin h' . As herein illustrated, the lever H is provided with a central recess or slot adjacent to the pivot h , within which slot the end of the arm H^4 is inserted, as clearly shown in Fig. 11.

From the construction described it is entirely obvious that when the shaft H' is revolved vertically oscillatory movement will be given to the arm H^4 through the medium of the crank-pin h' and slot h^2 described.

Upon the said lever H, beneath the oscillatory arm H⁴, is formed a rigid rearwardly-extending arm H⁵, the rear end of which is adapted for contact with the lower surface 5 of the oscillating arm H⁴. In the particular construction illustrated a set-screw H⁶ is inserted vertically through the end of the arm H⁵, and extends above the same so as to come in contact with the under surface of the oscillating arm H⁴, said set-screw serving as an adjustable stop or bearing-surface, which may be moved in adjusting the parts for operation and to compensate for wear. The spring G, acting on the actuating-lever E 10 above described, obviously operates to hold the free end of the said arm E and the type-disks elevated and to retain the downwardly-projecting arm E³ of said arm E at the forward limit of its movement, thereby 15 retaining the lever H in position with the end of the arm H⁵ in contact with the oscillating arm H⁴. It follows, therefore, that as the shaft H' is revolved the arm H⁵ will be pressed downwardly in opposition to the 20 spring G at each downward movement of the oscillating arm H⁴, thereby moving said lever H and the actuating-arm E in the same manner that it is moved by the use of the foot-lever I. The said arm H⁵, however, being unattached to the oscillating arm H⁴, the 25 parts may be actuated by the foot-lever without requiring the disconnection of any of the parts to enable the same to operate independently of the slot-and-pin connection 30 with the drive-shaft, it only being necessary that the shaft should be stopped with the crank-pin at the upward limit of its movement, so as to leave the oscillating arm above and free from the arm H⁵ when it is desired 35 40 to move the lever H and other parts by the foot-lever. The stoppage of the crank-pin at the point indicated may be accomplished by the use of any one of a great variety of forms of clutch devices well known to mechanics. The clutch device employed in the 45 present machine for stopping and starting the same is located between the belt-pulley H² and the crank-disk H³, and is indicated as a whole by H⁷, said clutch device being actuated by means of a foot-lever H⁸, connected 50 with the clutch by a rod H⁹. Said clutch device forms no part of the present invention, and is not therefore specifically shown and described herein. A spring I² is applied to the 55 foot-lever I to hold the same elevated and to thereby retain the arm I' thereof free from the lever H when the latter is moved by power in the manner described.

It is often necessary in the use of a number 60 of bering-machines of the character herein described that the number printed should be repeated two or more times, and devices have heretofore been made adapted to prevent rotation of the units-disk during two or more 65 consecutive movements of the type-disks toward the paper. My present invention embraces an improved device or attachment for

this purpose, which is made as follows: J J' J², Figs. 1, 3, 4, 6, 7, and 8, are notched disks, which are mounted upon a common shaft j, 70 the ends of which are supported in brackets j' j', affixed to the front surface of the plate C² near the upper end thereof and projecting forwardly from said plate. Said disks are splined to the shaft j and turn with the latter, and upon said shaft is placed a rigidly-attached ratchet-wheel J³. J⁴ is a spring-pawl mounted upon one of the guides a of the frame-arm A' at the upper end of said guide and constructed to engage the said ratchet-wheel J³. Said pawl J⁴ is so disposed as to turn the said ratchet-wheel a distance of one tooth at each reciprocation of the wheel. The said ratchet-wheel is provided with an even 80 number of teeth, and a number which is divisible by 2, 3, and 4, the particular wheel shown having twelve teeth. One of the disks, as J, is provided with six equidistant notches, another, as J', with four notches, and another, as J², with three notches, said notches operating in a manner and for a purpose hereinafter set forth. L is a vertically-arranged lever pivoted upon a horizontally-arranged stud l, which is attached to the side of the plate C², so as to sustain the said lever L in position 90 outside of and adjacent to the end of the frame-arm A', Figs. 4 and 6. The lower end of the said lever L is provided with a cam-plate L', located near the ratchet-teeth d' d' of the type-disk D and near the path of the spring-pawl F', which engages said ratchet-teeth and turns the end disk of the series, said cam-plate being curved upon its working-face in a circular curve concentric, or nearly so, with the type-disks. The spring-pawl F' is provided with 100 a rigid-arm F⁴, extending rearwardly from its pivot and provided preferably with an anti-friction roller f at its end. The said cam-plate L' may be moved toward and from the central axis of the type-disk by swinging the 110 lever L supporting it upon its pivot, and said cam-plate L' is so disposed with relation to the arm F⁴ of the pawl F' as to engage said arm and press the latter inwardly to hold the free end of the pawl out of engagement with the 115 ratchet-teeth when said cam-plate is in its position nearest the central axis of the disks. It follows from this construction that when the lever L is moved so as to bring the cam-plate nearer the central axis of the disks 120 the pawl F' will be held free from the ratchet-teeth, and when said lever is moved to carry the cam-plate outwardly or away from the axis of the disks the pawl will be allowed to engage said teeth, it being of course 125 understood that the said cam-plate is arranged to extend through or over an arc corresponding with the arc through which the roller f upon the end of the arm F⁴ of the pawl moves as said pawl is bodily oscillated. 130 By thrusting the cam-plate toward the center of rotation of the disks, therefore, the pawl will cease to act upon the ratchet-teeth, and the disks will remain stationary or will

not be turned. When the said cam-plate is swung away from the central axis of the disks, on the contrary, the end disk of the series will be turned one-tenth of a rotation at each 5 bodily reciprocation of the disks in the manner before described. The lever L is moved or swung so as to carry the cam-plate L' toward and from the axis of the type-disks by means of a movable bearing-finger adapted 10 to act upon one of the notched disks J J' J², and connected with the upper ends of the said lever L so that said lever will be moved as said finger is carried inwardly and outwardly in the turning of the notched 15 disks, said finger being carried toward the disks either by spring-pressure or by gravity, according to the arrangement employed. In a particular construction (illustrated in Figs. 1 to 14 of the drawings) the upper end of the 20 lever L is bent at right angles to the main part thereof, so as to form a transverse bar l', Fig. 8, extending past the said disks J J' J², parallel with the axis thereof. K is a finger arranged to slide upon the bar l', and 25 adapted to engage at its free end with the periphery of one of the disks J J' J². Said finger K is provided with a clamp-screw k or other clamping device by which the finger may be clamped immovably upon the said 30 bar l'. Said finger may be shifted upon the bar l' into position opposite either one of the disks J J' J², as desired. L² is a spring attached to the lever L and acting against an opposing part upon the plate C², (in the instance illustrated the arm C⁴), said spring acting to throw the upper end of said lever L and the transverse bar l' toward the notched 35 disks. The finger K is thus thrown and held in contact with the disk which is opposite it, 40 so that as the disks are rotated the finger will move inwardly or outwardly or toward and from the shaft supporting the disks, thereby transmitting a corresponding movement to the lower end of the said lever L, by which 45 the cam-plate L' is held adjacent the axis of the type-disks when the finger rests upon the outer periphery of the notched disk, and is held remote from the said axis when the finger sinks into one of the notches of 50 said notched disk. It follows that when the finger K is acting upon the outer periphery of one of the notched disks the cam-plate L' will be held in position to prevent the pawl F' from working, and when the said finger 55 drops into one of the notches of the disk the cam-plate will be thrown outwardly to allow the pawl to engage the ratchet-teeth upon the type-disk.

The machine shown in the drawings is 60 adapted to repeat the same number in printing either two, three, or four times, depending upon the disk J, J', or J², with which the finger K is engaged. The notches of the said disks J J' J² correspond in angular position 65 with the ratchet-teeth of the ratchet-wheel J³, so that one of said notches will stop at a point beneath the finger K during the termination

of one of the partial turns given to said ratchet-wheel by the action of the pawl upon the frame. It follows, therefore, that if the said 70 finger K is engaged with the disk J', having four notches, said finger will drop into one of said notches at each third reciprocation of the printing-disks, and the machine will repeat the same number three times. Similarly when 75 the finger is engaged with the disk J², having three notches, it will repeat four times, and when engaged with the disk J, having six notches, it will repeat twice before the number is changed by the shifting of the disks. 80 By providing a machine, therefore, with a plurality of notched disks, and with a sliding finger adapted to engage either of said disks, and by making the ratchet-teeth a multiple 85 of the number of notches in the disks, the machine may be made to repeat the number printed any number of times desired.

The notched disks J J' J², in addition to the deep or main notches therein, which allow the finger K to move toward the center of the 90 disks for causing the machine to repeat, in the manner described, are also provided with intermediate relatively shallow or small notches j² j³, Fig. 15, which notches correspond in angular position with the teeth of the 95 ratchet-wheel J³, so that at each partial rotation of the disks given by the action of the pawl J' upon said ratchet-wheel the finger K will engage either one of the large notches or one of the shallow intermediate notches j² j³, 100 above described. Engagement of the finger K with said notches j² j³ serves to hold the several disks from turning either backwardly or forwardly after the same have been moved by the pawl J' and ratchet-wheel. In view of 105 the advantages in point of simplicity of construction and operation obtained by the use of said shallow notches j² j³ in the disks a construction embodying the same is herein claimed as part of my invention. 110

In Figs. 16 and 17 are shown a somewhat different construction in devices for actuating the lever L from a series of notched disks arranged in the manner above described. In this instance K' is a swinging arm pivoted by 115 means of a pivot-pin k' to a standard k² at the upper end of the plate C². Said arm K' is arranged horizontally and extends forwardly with its free end over the disks J J' J². At said free end of the arm a transverse bar K² 120 is secured to the same, said bar extending over said disks J J' J² parallel with the shaft thereof, and upon said bar is mounted a sliding finger K³, arranged to engage the periphery of one of the said notched disks 125 in the same way as the finger K, hereinbefore described. The finger K³ is provided with a clamp-screw, by which it may be secured opposite either of the disks, as desired. In this construction the free end of the 130 arm K and finger K³ thereon are free to move vertically, and the weight of the parts keeps the said finger in contact with the disk engaged by it, with the aid of a spring, if nec-

essary. The upper end of the lever L in this construction extends to a point opposite the slide-bar K², and upon said slide-bar is placed a pin k³, which engages an inclined or cam slot l² in the upper end of said lever L. Said cam-slot l² is inclined in such manner that the said lever will be swung or moved as the disks revolve in the same manner as the said lever is moved by the devices hereinbefore described. F⁵, Fig. 6, indicates a short arm or finger-piece, which is attached to the end of the arm F⁴ of the pawl F', and is so arranged that the finger of the operator may be easily placed thereon for holding the pawl 15 out of engagement with the ratchet-teeth d', to free the end disk D from the pawl, when it is desired to turn the disk-supporting sleeve D' and disks thereon, as hereinbefore described.

20 In connection with a machine embracing the features above set forth, any suitable inking device for applying ink to the types prior to the making of each impression may be employed. A novel form of inking device embracing an oscillating inking-roller and ink-distributing disk, which is bodily moved to bring it into position for contact with the inking-roller, and which is provided with an improved means of supplying the same with 25 ink, is herein shown, and is constructed as follows: M is an inking-roller, which is mounted upon the end of an arm M', which arm is pivoted by means of a pivot-pin m to the side of the frame-arm A' opposite to that at which 30 the disk-turning devices above described are located. Upon the said arm M', adjacent to the pivot m, are two short prongs m² m³, which are located in position to be engaged by a horizontally-arranged pin m', secured to the 35 reciprocating plate C², which carries the disks. When the disks are at the upward limit of their movement the pin m' engages both of said prongs and holds the inking-roller at a point slightly forward of the row of types, which are in position for printing. As the 40 disks descend, the said pin m' presses downwardly upon the prong m³, thereby swinging the roller M backwardly past the row of types, which roller as soon as the pin leaves said 45 prong m³ is carried still farther backward by the action of a spring M³, which is attached to said arm M' and to an adjacent part of the machine. As the type-disks rise, the pin m', when said disks are near the upward limit of 50 their movement, passes the lower prong m³ and strikes the prong m², (which will be commonly somewhat longer than the lower prong,) swings forward the said arm M', and thereby 55 carries the inking-roller forward beneath the type-disks. N is the inking-disk, which is located at the rear of the type-disks in position for contact therewith of the inking-roller when said roller is thrown backwardly or away from the type-disks by the device above described. Said inking-disk is mounted upon 60 the end of a shaft N', which is rigidly attached to a block or hub N², which has bearing upon

the lower end of a swinging arm O, pivoted at o to the frame-arm A'. The pivotal connection between the hub N² and the arm O is herein shown as formed by a stud n, Fig. 9, upon the hub, which stud passes through a bearing-aperture in the lower end of said arm O, a collar n' being placed upon the end of the stud to hold the same in engagement 75 with the arm. The connection of the disk-supporting arm N' with the arm O, in the manner described, allows the said disk to swing in a vertical plane, while the pivotal connection of the arm O with the frame permits a bodily movement of said disk toward and from the type-disks. The hub N² is provided with two rigid arms N³ N⁴, arranged nearly at right angles with each other, the arm N³ extending upwardly and the arm N⁴ 80 extending rearwardly therefrom when the disk is in its normal position. O' is a link connecting the free end of the arm N⁴ with the frame-arm A', said link being pivoted to the frame-arm at a point considerably at the 85 rear of the arm O, so that the link stands at a downward and forward inclination of about forty-five degrees. O² is another link connecting the upper end of the arm N³ with the actuating-arm E, by which motion is given to the 90 type-disks. Said arm O² is also inclined downwardly and forwardly from its point of connection with the arm E, so that when said arm E is depressed, the arm N³ is thrown forwardly, thereby turning the hub N² in a direction to swing the disk N downwardly. The link O' serves to hold the arm O from 95 movement, except when the arm N³ and disk are moved in the manner described, when said link O' causes a backward movement of 100 the arm O and a bodily rearward movement of the inking-disk, in the manner clearly illustrated by the dotted lines in Fig. 5 of the drawings. The inking-roller M is so disposed with relation to the face of the disk N that 105 it will come in contact with the lower part of said disk shortly after the type-disks begin 110 their downward movement, the parts being shown in full lines in Fig. 5 in position occupied by them at the moment the inking-roller is brought in contact with the inking-disk. After the inking-roller is brought 115 against the disk the further downward movement of the actuating-arm E swings or carries the inking-disk downwardly and rearwardly, so that the inking-roller will move or 120 roll over the face of said inking-disk, the roller being held against the disk in this movement of the same by the action of the spring M³. The position of the parts after 125 the actuating-arm E has completed its downward movement is illustrated in dotted lines in said Fig. 5. This bodily movement of the inking-disk, combined with its swinging movement about the pivot n, causes the face 130 of the disk to move backwardly in a nearly straight line, so that the inking-roller M remains practically immovable during such movement of the inking-disk. The spring

M³ allows such slight movement or yielding of the inking-roller as is rendered necessary by the slight curvature of or irregularity in the path of the inking-disk, due to the compound movement produced by arrangement of the parts supporting it.

In inking devices as heretofore made, wherein the bodily motion of the inking-roller is prolonged in order that the same may pass over the inking-disk, the extent of such bodily movement is so great as to require a very rapid motion of the roller, thereby not only tending to rapid wearing out of the parts, but rendering liable the soiling of the paper being printed or neighboring articles by the casting off of particles of ink from the surface of the roller when the latter is suddenly stopped at the termination of its outward movement. In the construction described not only is the inking-disk brought close to the type-disks, but the inking-disk itself is moved to cause the roller to come in contact with all parts of the disk, so that such movement of the disk lessens the bodily movement of the roller necessary for suitably inking the type.

The machine shown in the accompanying drawings is provided with a novel and convenient ink-supply device or fountain for supplying ink to the surface of the inking-disk N. Such ink-supply device is shown in Figs. 9 and 10, and is made as follows: P is an ink-fountain, herein shown as consisting of a stationary piston P' and a movable hollow cylinder P², having a central screw-stem p, which engages a screw-threaded aperture at the center of the piston, said cylinder being adapted to contain ink, which is forced through passages p' p' in the piston by turning the cylinder so as to move the threaded stem p through the piston and thereby advance the piston into the cylinder. These devices for holding and expelling the ink are substantially similar to those heretofore used in a well-known form of lubricating device and are not in themselves essential to the operation of the invention, inasmuch as other forms of ink-supplying receptacles or fountains—as, for instance, a fountain acting by power or by gravity—may be substituted for the particular one herein shown with substantially the same result. P³ is a pipe or tube attached to the piston P' and communicating with the exit-passages p', which lead from the interior of the cylinder. The arm N', which sustains the disk N, is hollow and is adapted to receive the tube P³, which tube is made of such length that when inserted in the said arm its end is flush with the surface of the said disk. In the particular construction of the parts illustrated the ink-supply tube P³ is inserted in a projection p² of the piston P' at right angles to the latter, and the hub N², to which the arm N' is attached, is recessed or slotted to receive the said part p² of the piston, so that when the said tube P³ is inserted into the said arm N' the part p²

will extend outwardly through the slot or recess n⁵ of the hub, and the fountain will thereby be sustained with its axis at right angles to the said arm N'. The fountain P is desirably located in this manner in order that it may stand in position convenient to be grasped and turned by the operator for feeding ink to the disk, it being entirely obvious that if the tube P³ were arranged in line with the axis of the cylinder P² the fountain would stand at the rear of the hub N² and in a position exceedingly inconvenient for the operator. The slot or recess n⁵ of the hub N² is desirably made sufficiently deep to allow the part p² of the fountain to pass into the notch in the said hub, and a locking device is provided for securing the fountain in place, (herein shown as formed by a wedge or key n⁶), which is inserted through a vertical slot in the hub behind the said part p² of the fountain, in the manner clearly shown in the drawings, Fig. 9.

The ink-supply tube may communicate at 90 its outer or exit end with a passage leading through the center of the disk to the outer face thereof, in which case the said tube will terminate short of the said outer face of the disk. I prefer, however, to provide the disk 95 with a central hole of sufficient size to receive the end of the tube P³ and to bring the said end of the tube flush with the surface of the disk. This construction I employ to enable 100 ink of one color to be easily substituted for ink of another color by removing one fountain and substituting another fountain containing another kind of ink. When the ink-supply tube P³ extends to the face of the inking-disk, it is only necessary in changing the 105 color to wipe off the face of the disk and then remove the ink-fountain and tube, when the inking-disk and connected parts will be left entirely clean and a new fountain containing ink of another color may be substituted 110 without liability of any admixture of the colors. In case the ink-supply tube did not extend to the face of the disk a hole or passage in the disk, forming a continuation 115 of the supply-tube, would be necessary for the passage of the ink, and it would be very difficult to entirely remove the ink from said disk and passage in changing from ink of one to ink of another color. As herein illustrated, 120 the tube P³ is provided with a reduced cylindric end p³, which fits in a small opening at the center of the said disk. The said inking-disk is adapted to turn or rotate freely upon the said shaft N', and, as herein shown, 125 it is held upon the arm N' by means of a spring-arm n², which is attached to the hub N², and the free end of which is bent at right angles to the arm N' and engages a circumferential groove n³, formed in a hub n⁴ upon the said disk N. Suitable devices may be 130 applied for turning the said disk N automatically through a portion of a rotation at each bodily reciprocation of the disk; but such turning devices are not necessary, inasmuch

as the disk may be rotated by hand at suitable intervals to cause the ink to be properly distributed thereon. In Fig. 3 of the drawings the said disk is shown as provided with a milled edge, by which it may be easily turned by the fingers of the operator.

Devices for supporting the work-table B and for moving the same vertically for purposes of adjustment in working upon books or piles of paper of different thickness are herein provided as follows: The bracket B', which immediately supports the table B, has sliding engagement with a vertical guide b of the bracket B², which, as before described, is cast upon the front face of the standard A. Q is a screw-shaft, which is mounted at its lower end in a bearing b', cast upon the bracket B² at the lower end of the latter and engaged at its upper end with an interiorly-screw-threaded lug or projection B⁴ upon the sliding bracket B'. Said screw-shaft is provided at its lower end above the bearing b' with a beveled gear-pinion q. Q' is an obliquely-arranged shaft mounted at its lower end in a bearing b², located at the lower end of the bracket B² adjacent to the bearing b' and having bearing at its upper end in a bracket B⁵, bolted to the bracket B² in the manner illustrated. Said shaft Q' is provided near its lower end with a beveled gear-pinion q', intermeshing with the beveled gear-pinion q of the shaft Q, and is provided at its upper end with a hand-crank Q², by which said shaft Q' may be turned for giving rotary movement to the screw-shaft Q. Said shaft Q' is disposed in an inclined position, in the manner illustrated, so as to bring the crank Q² at one side of and below the work-table and in position convenient for the operator. When the shaft Q is rotated by turning the crank Q², the table will be raised and lowered by the sliding of the bracket B' upon the guides b. R is a traveling band or ribbon adapted to pass beneath that part of the surface of the table which comes opposite the type-disks, said traveling band being employed in paging books and doing similar work where the numbers are printed on both sides of the paper, and the sheets are inserted singly or one by one beneath the type-disks in printing, it being entirely obvious that ink from the printed numbers on one side of the sheets may be struck off or transferred to the supporting-surface below it when the pressure is brought upon the opposite side of the sheet in making an impression thereon, so that the traveling band constantly presents a new surface beneath the paper, and thereby avoids any accumulation of the transferred ink at one point and the soiling or defacement of the work thereby. A similarly-located traveling band has heretofore been used, the only features of novelty in connection with said band herein illustrated being embraced in the devices shown for giving movement to the same. The table B is recessed or slotted to receive

the upper end of the standard B', which latter supports the plate B³, which receives the pressure of the type-disks, and also supports the guide-rollers r r', by which the band is sustained in such manner that it may pass over said plate B³. r² indicates a third guide-roller for supporting the lower or under part of the band free from the adjacent parts of the bracket B², and r³ is another guide-roller for the lower portion of the band, which roller r³ is mounted upon a supporting-arm R², attached to the bracket B². Attached to the said roller r³ is a ratchet-wheel r⁴. R³ is a rocking lever mounted concentrically with the said roller r³ and ratchet-wheel r⁴ and carrying a spring-pawl r⁵, which engages the teeth of said ratchet-wheel. R⁴ is a connecting-link which is pivoted at one end to the swinging arm R³ and at its opposite end to the lever H, hereinbefore described. Said link R⁴ serves to transmit the oscillatory movement of the said lever H to the swinging arm R³, and to thereby move said arm so as to carry the pawl r⁵ over the ratchet-wheel r⁴, and thus turn the same continually during the operation of the machine. Said ratchet-wheel being rigidly attached to the roller r³, the same is turned with the ratchet-wheel, and the band R thereby moved or shifted forward a short distance each time the type-disks are actuated and an impression is made.

An important advantage is gained in a machine arranged, as shown, with a type-disk mounted upon a stud, which is supported by a single arm C⁴, located at one side of the type-disks, by arranging the devices by which the type-disks are turned at that side of the disks nearest the said supporting-arm C⁴, for the reason that this construction enables the several disks to be removed from the supporting-stud without disturbing or requiring the removal of the disk-turning devices.

I claim as my invention—

1. The combination, with the frame and type-disks, of means for sustaining and giving motion to the disks, consisting of a supporting-arm pivoted upon the frame and affording the sole support for the disks and an actuating-arm pivoted upon the frame independently of the supporting-arm and having elastic or yielding connection with the said supporting-arm, and means for giving bodily movement to the disks connected with said actuating-arm, substantially as described.

2. The combination, with the machine-frame and type-disks, of means for sustaining and giving motion to the disks, consisting of an oscillating arm pivoted to the frame and supporting the disks at its free end and an actuating-arm pivoted upon the frame independently of the supporting-arm and having elastic or yielding connection with the supporting-arm, said frame being provided with an overhanging rigid arm having lateral guides adjacent to the free end of the supporting-arm and engaging the sides of the said sup-

porting-arm for guiding the latter and the type-disks in their vertical movement, substantially as described.

3. The combination, with the machine-frame 5 and type-disks, of a supporting-arm pivoted to the frame, a plate C², attached to the end of said arm, at the lower end of which plate the type-disks are mounted, said plate being provided with a recess in its rear or inner 10 surface, an actuating-arm also pivoted to the said frame and engaged at its free end with the recess in said plate C², and a spring inserted in said recess beneath the free end of said actuating-arm, substantially as described.

15 4. The combination, with the type-disks and machine-frame, of a reciprocating disk-supporting plate provided with a single arm having a stud upon which the type-disks are mounted, and devices for turning the disks 20 located at that side of the said disks nearest the said supporting-arm, substantially as described.

5. The combination, with the type-disks and machine-frame, of a reciprocating disk-supporting plate provided with a single arm having a stud upon which the type-disks are mounted, and means for turning the said disks, comprising an oscillating lever mounted upon the said stud between the type-disks 30 and the arm and provided with a pawl for actuating the disks, substantially as described.

6. The combination, with the machine-frame and type-disks, of a reciprocating plate for supporting the disks, provided with a supporting-arm located at one side of the disks only and having a horizontal stud on which the disks are mounted, devices for turning the disks, comprising an oscillating lever mounted upon the stud between the disks and the said 35 supporting-arm, and a removable cap or collar for holding the disks upon the stud, whereby the disks may be removed from the machine by slipping them endwise from the said stud, substantially as described.

45 7. The combination, with the type-disks and a stud supporting the same, of a sleeve interposed between said stud and the disks and provided with collars at its ends for holding the disks upon the sleeve, said sleeve being adapted to turn freely on the stud, and a catch or locking device consisting of interlocking parts upon the said stud and sleeve constructed to engage each other at one position only of the sleeve for detachably holding 50 said sleeve from turning upon the said stud when the disks are in working position, substantially as described.

8. The combination, with the type-disks and the machine-frame, of a reciprocating plate provided with a single arm having a stud upon which the type-disks are mounted and provided with collars or shoulders to hold the disks upon the sleeve, a sliding pin mounted in the said arm and engaging a notch 60 or recess in the said sleeve, a spring applied to move said pin in a direction to engage the sleeve, and means for holding the said pin

free from the sleeve against the action of the spring, substantially as described.

9. The combination, with the type-disks 70 and machine-frame, of a reciprocating plate provided with a single arm having a stud upon which the type-disks are mounted, a sleeve interposed between the stud and the disks and provided with collars or shoulders 75 at its ends to hold the disks upon the sleeve, and means for turning the disks, comprising an oscillating lever mounted upon the stud between the said disks and the arm and provided with a pawl for turning the disks, substantially as described.

10. The combination, with the machine-frame and type-disks, of means for turning the disks, embracing an oscillating spring-pawl and a repeating device comprising a 85 movable cam-plate adapted to engage and hold the said pawl out of action in one position of the said cam-plate, a rotating notched disk, means for giving a partial rotation to the notched disk at each reciprocation of the 90 type-disks, and a finger movable toward and from the said notched disk and held yielding against the periphery of the same, said finger being connected with and adapted to actuate the said cam-plate, substantially as 95 described.

11. The combination, with the type-disks and oscillating pawl turning the same, of a repeating device comprising a movable cam-plate adapted to hold the pawl out of action 100 in one position of said cam-plate, a series of rotating notched disks movable bodily with the type-disks, means for giving a partial rotation to the notched disks at each reciprocation of the type-disks, a slide-bar movable toward and from the said notched disks, and an adjustable finger movable endwise upon said bar and adapted to engage either of said disks as desired, said bar being connected with and giving motion to the said cam-plate, substantially as described.

12. The combination, with the machine-frame, the type-disks, and a plate C², supporting the same, of means for turning the disks, comprising an oscillating pawl, and a repeating device comprising a series of notched disks mounted upon said plate C², a finger movable toward and from the notched disks, a movable cam-plate adapted to engage the said pawl and hold the same out of action in one 115 position of said plate, and a lever pivoted upon the plate C² and supporting the said cam-plate, said lever being provided with a slide-bar, upon which said finger is mounted, substantially as described.

13. The combination, with the machine-frame and type-disks, of a plate C², supporting the type-disks, means for turning the disks, comprising an oscillating pawl and a repeating mechanism comprising a movable cam-plate engaging the said pawl and holding said pawl out of action in one position of the cam-plate, a lever pivoted to the plate C², attached 120 at one end to the said cam-plate, a notched

disk mounted upon the said plate C², said disk being provided with main notches and secondary or smaller notches j² j², means for turning said notched disk, and a finger adapted to engage the periphery of the said notched disk and connected with the said lever, and a spring holding the finger in contact with the notched disk, substantially as described.

14. The combination, with the machine-frame, the type-disks, and a reciprocating plate C², supporting the type-disks, of means for turning the disks, comprising an oscillating pawl and a repeating device consisting of a notched disk mounted upon the plate C², a movable cam-plate adapted to engage the pawl and arranged to hold said pawl out of action in one position of the cam-plate, a lever pivoted to the said plate C² and attached at one end to said cam-plate, a finger engaging the periphery of the said notched disk and connected with the said lever, a ratchet-wheel mounted on the said plate C² and connected with the said notched disk, and a pawl upon the machine-frame engaging and turning said ratchet-wheel in the reciprocatory motion of the plate, substantially as described.

15. The combination, with the machine-frame and type-disks, of a plate C², supporting the type-disks, means for turning the type-disks, comprising a pawl provided with an arm F⁴, extending rearwardly from its pivot, and a repeating device comprising a cam-plate movable toward and from the axis of the type-disks, and adapted to engage and press inwardly the said arm F⁴ of the pawl, a pivoted lever supporting said cam-plate, a notched disk, means for turning the notched disk, and a finger movable toward and from the said notched disk and engaging the periphery of the latter, said finger being connected with and adapted to actuate the said pivoted lever which supports the said cam-plate, substantially as described.

16. The combination, with the machine-frame, type-disks, and a pivotally-supported actuating-arm therefor, of means for actuating said arm both by power and by the foot of the operator, comprising a pivoted lever H, engaging and giving motion to the actuating-arm, said lever H being provided with a rigid arm H⁵, an oscillating arm H⁴, located over and adapted to engage the said arm H⁵, a crank-pin giving oscillatory movement to said oscillating arm, a spring applied to move the actuating arm in one direction, and a foot-lever engaged with said lever H and adapted to actuate the same independently of the power-driving devices, substantially as described.

17. The combination, with the machine-frame, type-disks, and pivotally-supported actuating-arm, of a spring moving said arm in one direction, a lever H, engaged with said actuating-arm, provided with a rigid arm H⁵, a horizontally-arranged shaft H', provided with a crank-pin, an oscillating arm H⁴, adapted to engage said arm H⁵ and provided

with a longitudinal slot engaged with said crank-pin, and a foot-lever engaging said lever H, substantially as described.

18. The combination, with the type-disks, of a machine-frame embracing a hollow or tubular standard, provided with an overhanging arm or goose-neck at its upper end, a curved actuating-arm E, pivoted at the upper end of the hollow standard within the same and extending through the goose-neck, said actuating-arm being provided with a depending arm E³, extending below its pivotal point, a vertically-arranged lever H, pivotally supported within the hollow standard and engaged at its upper end with the arm E³ of the actuating-arm, a spring applied to move said actuating-arm in one direction, and a foot-lever I, pivoted at the base of the frame and extending upwardly within the tubular standard and engaged with the said lever H, substantially as described.

19. The combination, with the machine-frame and type-disks, a reciprocating plate supporting the disks, and an inking-disk, of an inking-roller, an arm M', supporting said roller, a pin m' upon the said reciprocating plate adapted to engage said arm for moving the inking-roller, and a spring applied to and acting on said arm M' to give further movement to said arm and to the inking-roller after the pin has left the same, substantially as described.

20. The combination, with the machine-frame and type-disks, a reciprocating plate supporting the disks, and an actuating-arm giving movement to said plate, of an oscillating inking-roller, an inking-disk N, a block or hub N², supporting said inking-disk and provided with arms N³ N⁴, a swinging arm O, having pivotal connection with the frame and affording support for said hub N², a link O', connecting the arm N⁴ with the machine-frame, and a second link O², connecting the arm N³ with the actuating-arm E, substantially as described.

21. The combination, with an inking-disk and a support upon which the disk is mounted and turns, of means for supplying ink to the disk, comprising an ink-receptacle and a passage leading therefrom through said support to the surface of the inking-disk, substantially as described.

22. The combination, with an inking-disk, of means for feeding ink to the same, comprising an ink-receptacle and a tube attached to the receptacle and extending through the disk to the working-face thereof, the end of said tube being flush with the said working-face of the disk, substantially as described.

23. The combination, with an inking-disk and a tubular arm affording pivotal support for the same, of a removable ink-supplying device comprising an ink-receptacle, and a tube attached to the receptacle and extending through said tubular arm and communicating at its end with the working-face of the disk, substantially as described.

24. The combination, with the machine-frame and type-disks, of an oscillating ink-roller and inking-disk, a block or hub N^2 , provided with a swinging tubular arm affording 5 pivotal support for said inking-disk, means connected with said block or hub for giving oscillatory motion to the inking-disk, an ink-supplying device comprising an ink-receptacle, and a tube attached to the receptacle and 10 adapted for insertion through said hub and tubular arm, said tube being in communica-

tion with the working-face of the disk, and a locking device upon the hub engaging said tube, substantially as described.

In testimony that I claim the foregoing as 15 my invention I affix my signature in presence of two witnesses.

SAMUEL K. WHITE.
